CLAIM

The ornamental design of the booster car seat base, as shown and described.

DESCRIPTION

FIG. 1 is a perspective view of the booster car seat base showing the design of my invention;

FIG. 2 is a right side view thereof;

FIG. 3 is a rear view thereof;

FIG. 4 is a front view thereof; and,

FIG. 5 is a top view thereof.

The left side view is a mirror image of the right side view.

The bottom of booster car seat base is plain and unadorned.

FIG. 1

FIG. 2

FIG. 3

FIG. 4

FIG. 5
